FOLDING POSTCARD OR WINDOW DISPLAY

Valentine Sandberg, Teaneck, N. J.

Application September 24, 1938, Serial No. 231,532

3 Claims. (Cl. 46—35)

This invention relates to new and useful improvements in a folding postcard or window display.

The invention has for an object the construction of an article as mentioned which is characterized by a pictorial illustration, cutout features of a principal subject or subjects standing out in relief from said illustration, and a means for folding said illustration and cutout features in a particular manner, in one operation.

More specifically, the invention contemplates the construction of the device from a strip of material having a background panel portion with a pictorial illustration, an adjacent panel portion for forming the base upon which the display may rest, and an upper panel associated with the latter-mentioned panel portions in a certain way to assist in supporting a cutout feature member of a principal subject standing out in relief from said illustration.

Still further the invention proposes providing a hook or similar element upon the upper panel portion adapted to releasably engage the background panel in a manner so that when the background panel, with the pictorial illustration, is folded down the upper panel portion will be correspondingly moved and so the device will be folded in one operation.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a folding postcard or window display constructed according to one form of this invention, and illustrated in the closed position.

Fig. 2 is a perspective view of the article shown in Fig. 1 fully open.

Fig. 3 is a transverse vertical sectional view taken on the line 3—3 of Fig. 2.

Fig. 4 is a transverse vertical sectional view on the line 4—4 of Fig. 1.

Fig. 5 is a bottom elevational view of Fig. 1.

Fig. 6 is a fragmentary horizontal sectional view on the line 6—6 of Fig. 3.

Fig. 7 is a developed view of the same sheet from which the article is formed.

The folding postcard or window display, according to this invention, is constructed from a strip of material having a background panel portion 10 with a pictorial illustration 11 painted

or imprinted thereon. Adjacent the background panel 10 there is an adjacent panel portion 12 for forming a base upon which the display may stand as hereinafter more fully explained.

A narrow panel portion 13 is arranged on the front end of the base panel portion 12. An upper panel portion 14 continues from the top of the narrow panel portion 13 and is adapted to extend parallel to the base panel portion 12. The various panel portions are formed by score lines 10 arranged transversely in the strip of material from which the panel portions are divided. A score line 15 (see Fig. 7) serves to separate the panel portions 10 and 12. Score line 16 separates the panel portions 12 and 13; score line 17 separates the panel portions 13 and 14.

A hook 18 is formed upon the free end of the upper panel portion 14 and is adapted to be releasably connected with the background panel portion 10. There is a slot 19 formed in the background panel portion 10 and arranged slightly offset relative to the hook portion 18 so that when the hook portion engages the slot 19 it will extend over one of the ends of the slot and so hold the parts together. This is clearly shown in Fig. 1. In order to disengage the hook 18 from the slot 19 it is necessary that the panel portion 14 be flexed slightly laterally relative to the panel portion 10.

A cutout feature member is provided with principal subjects 20a and 20b standing out in relief from the illustration 11 and extending up through slots 21 formed in the upper panel portion 14. The slots 21 serve to assist in supporting the principal subjects 20a and 20b in vertical positions. These principal subjects are connected with the base panel 12 as hereinafter more fully described.

In the assembled condition of the device the panels 12 and 14 are superimposed as shown in Figs. 1 and 2, while the background panel 10 is disposed to form a background above these panels. In the open condition of the article shown in Fig. 2 the panel 14 is parallel to and spaced the distance of the height of the narrow panel 13, from the base panel 12. When the panel 10 is pivoted downwards to be superimposed upon the panel 14, the panel 14 will be forced slightly laterally to flatten out the narrow panel 13 and substantially force this panel into the same plane as the base panel 12. This is the state of the article shown in Fig. 1.

From the free edge of the background panel 10 there projects a tab 22. This tab is engageable beneath a complementary tab 23 formed from

the material of the base panel 12. Fig. 5 shows these tabs interlocked. The outer face of the background panel 10 is imprinted with material 24 representing the customary printed matter upon a blank postcard. Thus the device may be used as a postcard. When constructed of a large size the device may be used as a novelty window display.

The principal subjects 20^a and 20^b, in the form of the invention illustrated in Figs. 1 to 7 are die cut from the material of the base panel 12. These principal subjects are connected along one of their bottom edges, namely the edges 20' (see Fig. 7) with the material of the base panel 12, 13 and are formed with a strip portion 20^{aa} which extends closer to the edge 12' than the die cut edge 20' of the principal subject 20^a. The edges 20' are substantially located beneath the slots 21 (see Fig. 3) when the article is in the fully open position. It should be recognized that the material of the upper panel 14 to the sides of the slots 21 engage the faces of the principal subjects 20^a, 20^b, and serve to hold these subjects in the vertical position in an open condition of the display, and serve to move the subjects down flat against the top of the panel 14 when the display is folded to the closed position. It is only necessary to move the background panel 10 to open and close the display. The end 21' of the slot 21 is further away from the edge 12' of the postcard than the end of the strip portion 20^{aa} so that the area 14' may rest on the strip 20^{aa}, thereby spacing the panel 14 from the base panel 12. This spacing 13' is preferably 35 made equal throughout, between the panels 14 and 12 by making the width of strip 20^{aa} correspond with the inner size of the narrow panel portion 13.

It is to be understood that the card may be 40 of any suitable size and material, and contain any desired illustration and wording.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I 50 claim as new, and desire to secure by United States Letter Patent is:

1. A folding postcard or window display, comprising a strip of material having a background panel portion with a pictorial illustration, an adjacent panel portion for forming a base upon which the display may stand, a narrow panel portion upon the front end of said base panel portion, and an upper panel portion continuing

from the top of said narrow panel portion and extending parallel to said base panel portion, a hook on said upper panel portion releasably engaging said background panel, and a cutout feature member of a principal subject standing out in relief from said illustration and extending through slots in said upper panel portion and connected with said base panel portion, one of said principal subjects being cutout from the material of the base panel and being formed with a 10 spacing strip to space the upper panel portion from the said base portion, in conjunction with the said narrow panel.

2. A folding postcard or window display, comprising a strip of material having a background panel portion with a pictorial illustration, an adjacent panel portion for forming a base upon which the display may stand, a narrow panel portion upon the front end of said base panel portion, and an upper panel portion continuing from 20 the top of said narrow panel portion and extending parallel to said base panel portion, a hook on said upper panel portion releasably engaging said background panel, and a cutout feature member of a principal subject standing out in relief from 25 said illustration and extending through slots in said upper panel portion and connected with said base panel portion, one of said principal subjects being cutout from the material of the base panel and being formed with a spacing strip to space 30 the upper panel portion from the said base portion, in conjunction with the said narrow panel, the width of said spacing strip and the narrow panel being equal in size.

3. A folding postcard or window display, comprising a strip of material having a background panel portion with a pictorial illustration, an adjacent panel portion for forming a base upon which the display may stand, a narrow panel portion upon the front end of said base panel portion, and an upper panel portion continuing from 40 the top of said narrow panel portion and extending parallel to said base panel portion, a hook on said upper panel portion releasably engaging said background panel, and a cutout feature 45 member of a principal subject standing out in relief from said illustration and extending through slots in said upper panel portion and connected with said base panel portion, one of said principal subjects being cutout from the material of the base panel and being formed with a spacing strip to space 50 the upper panel portion from the said base portion, in conjunction with the said narrow panel, the said slots are so arranged as to permit the principal object to pass through the 55 same and to prevent the said spacing strip from passing through the slot.

VALENTINE SANDBERG.
